UNITED STATES PATENT OFFICE.

HARRY WALTER JONES, OF SAN FRANCISCO, CALIFORNIA.

COMPUTING-MACHINE.

1,140,684.

Specification of Letters Patent. Patented May 25, 1915.

Application filed November 26, 1913. Serial No. 803,265.

To all whom it may concern:

Be it known that I, HARRY WALTER JONES, a citizen of the United States, residing in the city and county of San Francisco and State of California, have invented certain new and useful Improvements in Computing-Machines, of which the following is a specification.

The present invention relates to calculating machines generally but more particularly to a type of machine by the employment of which one is enabled to quickly and accurately multiply figures, not by the long and tedious method employed in machines now in use, that is, by adding the multiplicand the number of times required, by the multiplier, but by multiplying the multiplicand successively by the units, tens and hundreds of the multiplier and after the last operation, obtaining the total result without any further operation of the machine.

The invention has for its principal objects, to provide a multiplying machine which is capable of being operated to multiply any given number and after the answer thereof has been obtained, is capable of operation to prove the answer; to provide a structure having separate multiplicand and multiplier operating mechanisms; one in which the multiplier key is automatically restored to its normal position on the multiplication of the multiplicand by the operated multiplier, and one employing a novel form of computing means which when once set to correspond to the multiplicand may be multiplied by any number in the multiplier without the necessity of being reset.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying sheets of drawings wherein—

Figure 1 is a side elevation of my improved apparatus. Fig. 2 is a top plan view

of the apparatus, disclosing the multiplicand and multiplier buttons, the multiplicand setting lever, and the multiplier operating lever. Fig. 3 is a top plan view partly broken away, disclosing the carriage and carriage operating means, the multiplicand units and tens disks, the operating means therefor and the general arrangement of the parts within the casing. Fig. 4 is a sectional view on line 4—4 of Fig. 2, disclosing one row of multiplicand buttons, one of the controlling disks of tens denominations, the locking means therefor, the disk positioning segment and the arm for limiting the movement of the segment. Fig. 5 is a sectional view taken on line 5—5 of Fig. 4, disclosing several of the multiplicand buttons and the means for restoring the same to their normal position. Fig. 6 is a detail view of one set of units and tens controlling disks, disclosing the positioning of the same relative to each other and the stepped seats for receiving the plungers controlling the indicating wheels. Fig. 7 is a sectional view taken on line 7—7 of Fig. 2, disclosing the multiplier buttons, the means for locking the disks on their shaft, and the means for rotating the disks when in their locked position relative to the operated multiplier button. Fig. 8 is a sectional view taken on line 8—8—Fig. 7, disclosing more fully the disk locking mechanism. Fig. 9 is a sectional view on line 9—9—Fig. 8, disclosing the pawl and rack which controls the direction of movement of the multiplier handle. Fig. 10 is a sectional view taken on line 10—10 of Fig. 2, disclosing the movable carriage, the slidable frame for controlling the movement of the plungers and the means for controlling the sliding frame. Fig. 11 is a sectional view of the sliding frame and plungers taken on line 11—11 of Fig. 10. Fig. 12 is a detail view of the carriage, the indicating wheels carried thereby, the wheels for operating the indicating wheels and the means for retaining the carriage in elevated position when it is desired to manually reset the indicating wheels. Fig. 13 is a sectional view taken on line 13—13 of Fig. 2, disclosing the carriage, the devices for advancing the same, the controlling disks, the indicating and actuating wheels, the racks and plungers associated therewith, the plunger controlling frame, and the means for permitting the movement of the racks in one direction when there is

a numeral to carry. Fig. 14 is a view similar to Fig. 13 but with the plunger controlling frame advanced, the plunger in one of the recesses in the controlling disk and the pin of the indicating wheel in a position to trip the rack controlling means to permit the carrying of a numeral to one of the indicating wheels in advance. Fig. 15 is a sectional view taken on line 15-15 of Fig. 13, disclosing the carriage and indicating wheels carried thereby, the units and tens wheels, the racks for operating the same in one direction, and the springs for operating in the reverse. Fig. 16 is a sectional view taken on line 16-16 of Fig. 13, disclosing the pin operated mechanism for permitting the further rotation of the indicator wheel in advance when it is necessary to carry a numeral. Fig. 17 is a view in section taken on line 17-17 of Fig. 3, disclosing a portion of the carriage reversing mechanism. Fig. 18 is a detail view on line 18-18 of Fig. 3, disclosing the carriage actuating pawl and ratchet mechanism. Fig. 19 is a view in plan of the mechanism for reversing the movement of the carriage on the initial step when proving the multiplied sum. Fig. 20 is a diagram of the steps of multiplication of a given sum. Fig. 21 is a diagram of the sums displayed on the indicator wheels during the forward and backward movement of the multiplier lever when multiplying the sum set forth in Fig. 20. Fig. 22 is a diagram of the sums displayed on the indicator wheels during the forward and backward movement of the multiplier lever when proving the sum total of the multiplied figures set forth in Fig. 20.

Throughout the specification the terms front and forward designate that portion of the machine adjacent the key banks or in a direction toward the same, and the terms rear and backward designate that portion of the machine adjacent the indicating wheels or in a direction toward the same.

Referring more particularly to the drawings, wherein like numerals of reference indicate corresponding parts throughout the several views—1 designates a suitable housing, provided with an enlarged rear portion 2 formed with a hinged cover section 3 which is provided with suitable apertures 4 preferably arranged in alinement.

Mounted in the casing are the side members 5 and 6 of the supporting frame, which support the rotatable disk supporting shaft 7 on which is rotatably mounted the spaced units and tens controlling disks 8 and 9, (Figs. 3, 4, 6 and 8) and mounted between each pair of disks and secured to the same are the pinions 10, each of which intermeshes with a segmental sector 11 mounted on a tubular shaft 12, which is rotatably supported on a shaft 13. Each segmental sector is rotated in a direction toward the

rear of the casing by an independent spring 14, one end of which is secured to the sector adjacent the hub thereof and the opposite end operates through a slot 15 in the tubular shaft 12 and is secured to the shaft 13. 70

Each sector is provided with an angularly extending arm 16, which, when the sector is operated by its controlling spring, strikes the lower end of a depressed multiplicand button or key 17 associated therewith. 75

The multiplicand buttons or keys 17 are of a type similar to that employed in the better known forms of adding machines and are arranged in rows of nine and the rows beginning from the right in Fig. 2 designating units, tens, hundreds, thousands and tens-thousands, but it is to be understood that any denomination of numbers may be employed. Each button or key 17 operates through a suitable guide opening 18 in the 80 housing 1, and also through an opening 19 in a plate 20, supported by the side members of the supporting frame. Slidably mounted on the plate 20 is a restoring plate 21, provided with a plurality of oval openings 22 through which the buttons or keys operate, and positioned adjacent each opening is a beveled lug 23 Fig. 5 which is adapted to contact with the under-side of a shoulder 24 carried by the button or key, the two being 95 normally held in disengaged position by a spring 25 coiled about a stud 26, and positioned between the head thereof and the side frame of the machine. Outwardly bowed spring fingers 27 are carried by the buttons 100 or keys and operate against the side of the openings 19 to frictionally retain the same either in a raised or lowered position.

The multiplicand disk setting mechanism Figs. 3 and 7 comprises a hand lever 28 mounted on the shaft 13 and connected through a link 29 with an arm 30 secured to a shaft 31, rotatably mounted in the side members of the frame, and carried by said shaft in a position to coöperate with suitable lugs 33 formed on said segmental sectors is a bar or rod 34, which, when in its lowermost position, as in full lines—Fig. 4, restores the segmental sectors to their normal inoperative position, and when in a dotted line position, as in Fig. 4, permits the sectors to be rotated on their supporting shaft by the springs controlling the same, in order to properly present the controlling disks in accordance with the actuated multiplicand buttons. The hub portions of each of the controlling disks Figs. 6 and 8, as well as pinions 10 connected thereto, are formed with a plurality of radial slots 35, which are adapted to receive a locking bar 36 positioned in a channel 37 formed in the shaft 7 and said bar is provided with angularly disposed guide slots 38 in which operate the pins 39 extending transversely of the channel 37, the locking bar being nor-

105 110 115

120 125 130

mally forced to its lowermost position in disengagement from the slots 35, by a coiled compression spring 40.

Mounted on the outer end of the shaft 7 is a collar 41 formed with a peripheral groove 42, and retained in position on said shaft in contact with said locking bar by a pin 43, which extends through a transverse channel 44 formed in said shaft. Suitable pins 45 at the ends of bifurcated arms 46 formed on a lever 47 operate in the peripheral groove 42 and force the locking bar inwardly and upwardly against the spring 40 and in a position to lock the controlling disks to rotate with the shaft 7. The lever 47 is pivoted to a lug 48 formed on the frame, and is provided on its end opposite from the bifurcated arms with a beveled surface 49 against which the beveled wedge 50, carried by the lower end of the lever 28 contacts when the lever is pulled downwardly as in Fig. 7.

The units and tens controlling disks 8 and 9 of each pair are provided on their peripheries with stepped recesses as in Fig. 6, and are separated into ten sectors namely— A^0 , A^1 , A^2 , A^3 , A^4 , A^5 , A^6 , A^7 , and A^8 , which represent respectively the nine numbers and zero of a multiplicand. The sectors A^0 and A^1 of the tens disk 9 are formed without steps as the result of a zero or one multiplied by a single multiplier number does not contain a ten, but the sectors A^2 , A^3 , A^4 , A^5 , A^6 , A^7 , A^8 and A^9 contain respectively one, two, three, four, five, six, seven and eight steps, or one less step than the multiplicand number which they represent, as if any given single multiplicand number is multiplied by a single given multiplier, the highest tens possible in the result is of a numeral one less than the given multiplicand number. The sector A^0 of the units disk 8 does not contain any steps, as in multiplying a zero the result is zero. The A^1 sector of the units disk 8 is formed with nine steps which represent respectively the nine units possible when multiplying the numeral 1 by any given single multiplier number, the innermost step representing nine and the outermost step representing one. The remaining sectors A^2 , A^3 , A^4 , A^5 , A^6 , A^7 , A^8 and A^9 of the disk 8 are formed with suitable steps arranged in such manner relative to the steps in the respective sectors of the tens disks that the proper units numeral will be associated with the proper tens numeral in the result of a given multiplication of the respective numbers in the sectors, as, for example, referring to the A^0 sector, five multiplied by one equals 5, which is designated by the step 51 in the units disk which is of a distance of five single steps in the disk; five multiplied by two equals ten, which is designated by the single tens step 52 in the tens disk, and there being zero units, there is no unit step in the units

disk; five multiplied by three equals fifteen which is designated by one step 53 in the tens disk and five steps 54 in the units disk; five multiplied by four equals twenty, represented by two steps 55 in the tens disk and none in the units disk as the unit is a zero; five multiplied by five equals twenty-five, represented by two steps 56 in the tens disk and five steps 57 in the units disk; five multiplied by six equals thirty, represented by three steps 58 in the tens disk and none in the units disk, as the unit is a zero; five multiplied by seven equals thirty-five, represented by three steps 59 in the tens disk and five steps 60 in the units disk; five multiplied by eight equals forty, represented by four steps 61 in the tens disk and none in the units, as the unit is a zero, and five multiplied by nine equals forty-five, represented by four steps 62 in the tens disk and five steps 63 in the units disk.

In the respective sectors the results of the multiplicand represented thereby when multiplied by any single multiplier may be readily obtained by following the above example. In the operation of the device the disks 8 and 9 forming each pair are rotated simultaneously to properly position the multiplicand segments thereof to means herein-after described and in accordance with the operated multiplier button or key.

Secured to the shaft 7 adjacent the collar 41 is a hub 64, carrying an arm 65, pivotally connected by a link 66 with the lower end of an arm 67 Fig. 7 carried by the shaft 13, and the upper free end of said arm is adapted to move in the path of the row of multiplier buttons or keys 68 and contact with the lower ends of the same when they are depressed, the depressed button or key limiting the movement of the free end of the arm and regulating the rotation of the disks 8 and 9 and the shaft 7, by the coiled spring 69 which surrounds the shaft with one end secured thereto and the opposite end attached to the side frame. The multiplier keys or buttons 68 being of the same construction as the multiplicand buttons or keys, a description of the same is not thought necessary.

Mounted on a shaft 70 rotatably mounted in the side frame members 5 and 6 is an operating handle 71 and keyed to the shaft is an arm 72, which, when in its rearward-most position contacts with a pin 73 on the arm 65 and retains the same in the dotted line position—Fig. 7. A pivoted pawl 74 is carried by the arm 72 and the same operates over a segmental rack 75 secured to the frame and prevents the return movement of the handle until the same has completed its complete movement in the direction of its travel.

Positioned adjacent the rear end of the side frame members 5 and 6 and adapted to slide transversely of the same, is an

indicator wheel carrying carriage Figs. 3, 10 and 12, comprising end plates 79 which are connected by supporting rods 76 and 77 and rods 80 and 81, the rod 80 being provided for a portion of its length with a worm 82 which is received in a keyway 83 of a rotatable carriage advancing member 84 carried by the shaft 80, but prevented from longitudinal movement thereon by the hooked retaining members 85 carried by a support 86 and positioned one on either side of the advancing member 84. The member 84 Fig. 18 is provided with peripheral flanges 87 each formed with an oppositely disposed ratchet surface 88 and 89 which are engaged respectively by the pivoted pawls 90 and 91 carried by the arms 92 and 93 pivotally mounted to crank arms 94 and 95, mounted on the shafts 96 and 97 between collars 98, and said shafts extend through the side members of the frame and are connected at their ends by the plates 99 and 100. The shafts 96 and 97 and plates 99 and 100 are capable of slight transverse movement relative to the supporting frame members 5 and 6, to position the pawls 90 and 91 into operative engagement with their respective ratchets, to move the carriage one step either in a forward or reverse direction on each operation of the lever 71.

Positioned between the supporting frame member 6 and the plate 100 and surrounding the shafts 96 and 97 are coiled springs 101 which exert pressure on the end plate 100 and retain the shafts 96 and 97 in their limit of movement to the left, thus positioning the pawl 90 into operative relation relative to the rack 88 and disengaging the pawl 91 from its rack 89 to permit the indicator wheel carriage to be advanced to the right.

It is necessary in changing the operation of movement of the indicating wheel carriage from right to left or vice-versa to advance the carriage one step, in the direction of the desired movement, and this is accomplished in the reversing of the carriage in its movement from left to right by the following mechanism. The above shifting of the carriage is necessary in order to position the proper indicator wheels in mesh with the proper gear wheels on the initial operation of the lever 71, as after the last complete operation of the lever 71 in any multiplication or the proving thereof, the indicator wheels are in mesh with a gear at one side of the proper gear for their first movement in a reverse direction. Pivoted on a stud 102, projecting outwardly from the end plate 100 Figs. 17 and 19 is a crank arm 108, pivoted at one end to a finger plunger 104 slidably mounted on a guide 105 projecting outwardly from the end plate 100, and said finger plunger is retained in its outermost position by a coiled spring 106. The oppo-

site end of the crank arm is pivotally mounted to one end of a rod 107 slidably mounted in guides 108, formed on an arm 109, pivoted at one end to a lug 110 projecting from the side frame member 6. Pivotally mounted on the outer end of the arm 109 is a pawl 111, which is also pivotally connected, as at 112, to the outer end of the rod 107, and said pawl is formed with a beveled face 113 which is adapted to engage, when the finger plunger is pushed inwardly, certain of the ratchet teeth 114 formed on the shaft 80, moving the carriage one step to the right, and during this operation the end plate 100 is forced inwardly moving the frame to the right, disengaging the pawl 90 from its associated ratchets, and moving the pawl 91 into engagement relation with its associated ratchets. The frame is retained in its position of movement to the right by a catch 115 pivoted to a lug 116 on the frame 6 and said catch is normally forced downwardly to engage over the end member 100 by a spring 117 which compresses against an arm 118 formed above the catch 115.

The inner end of a trip arm 119 pivoted to a lug 120 carried by the frame member 6 is normally forced outwardly and into contact with the arm 118 by a spring 121, (Fig. 8) and the outer end of said trip arm is adapted to be engaged by a lug 122 carried by the shaft 80, on the movement of the indicator wheel carriage a given distance from right to left, the lug operating the trip arm to release the catch from the end plate 100 and permit the frame to be forced to the left by the spring 101, disengaging the pawl 91 from its associated ratchet and positioning the pawl 90 into operative relation relative to its ratchet.

Pivoted to the lower portions of the crank arms 94 and 95 is a rod 123 Fig. 13 which operates through a guide 124 and is provided on its lower end with an idler 126 which rests on an operating slide 127 formed with a raised portion 127', and which is mounted in a guide 128, and supported on a roller 129, and said operating slide is pivotally connected at one end to an arm 130 keyed to the shaft 70.

From the above construction it will be apparent that on each operation of the shaft 70 in a forward direction the crank arms 94 and 95 will be operated, and will in turn actuate the pawls associated therewith, which, in accordance with the one engaged with its rack will cause the indicator wheel carriage to move one step in the direction of its travel.

Loosely mounted on the opposite ends of the shaft 70 are arms 131 formed in their hub portions with a suitable cut out 132 in which operate the pins 133 Fig. 10 carried by the shaft, this construction providing a rotation of the shaft part way in either di-

rection before the pins strike the sides of the cut outs, to operate the arms.

The upper ends of the arms 131 Fig. 10 are pivotally connected by links 134 to levers 135, and other links 136, the levers 135 being connected to a shaft 137, and the links pivotally connected to the ends of a plunger controlling bar 138, which slides in suitable guide slots 135 in the side frame members 5 and 6. The plunger controlling slide bar 138 is provided with a plurality of transverse openings 139 which register with similar openings 130 in a stationary mounted guide bar 141, positioned between the side members 5 and 6 and directly in rear of the controlling disks 8 and 9.

Slidably mounted in the openings 139 and 140 are the plunger rods 142, Figs. 11, 13 and 14, each adapted to coöperate at one end with a units or tens disk, and each of the plungers, coöperating with the units and tens disks are formed on their opposite ends with racks 142', which engage respectively the upper and lower faces of the pinions 143 rotatably mounted on the shaft 144, and each mounting a toothed gear wheel 145 which are connected to the shaft by the springs 146 coiled in opposite directions so that on the forward movement of the plunger controlling bar the springs 146 will cause their respective units and tens wheels to rotate in the direction of the arrows—Fig. 13, forcing the plungers into their proper stepped recesses in the peripheral edge of the units and tens disks.

The gear wheels 145 are positioned to alternately engage the toothed peripheral edges 147 of the indicator wheels 148, mounted to rotate on a supporting shaft 40 carried by the indicator wheel carriage, and the operation of said gear wheels on the plungers being seated in their proper recesses in the controlling disks and withdrawn therefrom, will cause the indicator wheels to rotate and display the result of the multiplied sum through the openings 4.

Interposed between the plunger controlling bar 138 and the ends of the racks 142 are coiled springs 149' Figs. 11, 13 and 14 which on the return of the plunger controlling rod to its normal position, as in Fig. 13, will force the rear ends of the racks 142' against the free ends of dogs 150 and 150', formed at their front ends with stepped recesses 151, and pivoted to the shafts 152 adjacent which pivot points the dogs associated with the racks connected to the plungers of each pair of units and tens disks are normally maintained in contact with the transversely extending bar 153 by a spring 154. The rear end of each dog carries a spring 155 which engage in the notches 156 formed in a plate 157, slidably mounted in guides 158 in the side members 5 and 6 and said plate is normally retained in its for-

ward position by coiled springs 159, one mounted in each guide. The means for restoring the pawls to their normal position after being operated, in a hereinafter described manner, consists of a trip lever 160, Fig. 13, keyed to the shaft 137 and provided at its end with a tip 161 keyed as at 162 and yieldably connected to the lever 160 by a spring 163, and said tip on its upward movement actuates a curved arm 164 pivoted to a shaft 165, and connected by a link 166 to a lever 167, mounted on one of the shafts 152 and said lever is in turn connected by a link 168 to the sliding plate 157. It will be apparent that the movement of the trip lever in one direction will cause the tip 161 thereof to contact with the curved arm 164 and pass under the same, but on the movement of the trip lever in the opposite direction, the tip 161 thereof will not be permitted to swing when passing under the curved arm 164, but will engage the same, which, through its associated links and levers will move the plate 157 rearwardly and permit the springs 154 to draw the pawls to their normal position.

Projecting laterally from the indicator wheels 148 are pins 168, each adapted on a complete rotation of one of the wheels to contact with one end of a trip finger 169 (Figs. 12—13 and 14) positioned immediately in rear thereof and pivoted to the shaft 81 of the carriage, and on the movement of the carriage in either direction the fingers pass in coöperative relation between suitable upper and lower trip levers 170 and 171 Fig. 16, which are respectively pivoted to the shafts 172 and 173 and carry the pivoted hangers 174 and 175 which are respectively connected by the members 176 and 177, from which depend the respective links 178 and 179. The link 178 is connected to one end of a lever 180 pivoted to the plate 158 and contacts with the upper edge of the dog 150, and on the complete rotation of one of the wheels 148 when the carriage is traveling to the right is operated to press the dog downwardly, which will permit the rack 142' associated with a tens disk plunger, in its return movement, to be pushed rearwardly by the spring 149' into the first recess 151 thereof, which permits the indicator wheel to be rotated one numeral beyond that which would ordinarily take place. The link 179 and its associated parts is employed when the device is used for the proving of the multiplied sum, and the carriage is operated from right to left and said link is connected with a lever 181 pivoted to the rear of the plate 158 and contacts with the lower edge of the dog 150', and on the complete rotation of one of the wheels 148 in reverse direction, will operate the dog associated therewith upwardly and permit the rack 142' 130

associated with a units disk in its return movement to be forced by the spring 149' into the first recess 151 of the dog 150' which causes the indicator wheel to be rotated one numeral beyond that which would ordinarily take place.

After proving a multiplied sum, in a manner hereinafter described, it is necessary after the carriage has been moved its last step to the left, to manually advance the same one further step to the left in order that the indicator wheels will intermesh with the proper wheels 145, and this is accomplished by the finger 182 Fig. 15, adapted to 10 be forced into contact with the end plate 79 of the carriage, and pivoted to a lug 183 projecting outwardly from the frame member 5. The lug is normally forced outwardly by a coiled compression spring 184, 20 and is forced in contact with the end plate 79 by pressure exerted on a slidably mounted plunger 185 which is pivotally connected to the finger and extends exteriorly of the casting 1.

25 On each forward movement of the lever 71 an arm 186 secured to the opposite end of the shaft 70 therefrom, strikes a spring pressed pivoted dog 187 (Fig. 3) which is connected by a link 188 to a pivoted crank 30 arm 189 which is normally in contact with the head of the stud 26, operates the said which causes the restoring plate 21 to slide to the right, which movement restores all of the actuated keys to their normal position.

35 The restoring of the keys to their normal position does not in any way effect the sectors of the multiplicand disks as the same are retained in locked engagement on the shaft 7, but permits the multiplier arm 67 to 40 be moved to engaged relation with a newly operated button on the next rearward movement of the lever 71.

Should it ever become necessary to manually reset the indicator wheels, the carriage 45 is capable of pivotal movement upwardly on the shaft 76, which disconnects the indicator wheels from the gears 145, the carriage being maintained in its raised position by the pivoted catch 190 Fig. 12 formed with 50 the recess 191 therein, and which is forced rearwardly into engagement with the shaft 77 by the coiled spring 192.

The parts being assembled as in the drawings, the device is operated in the following 55 manner:—If it be desired to multiply 99 by 8, the multiplicand is first set up by operating the multiplicand buttons x and y representing 99. The lever 28 is now pulled forwardly which permits the springs 14 to 60 force the sectors of the first two pairs of units and tens disks to rotate the same the proper distance about the shaft 7, the arms 16 of the sectors limiting the movement thereof by striking the lower ends of the operated multiplicand buttons x and y (Figs.

2, 3 and 4). Further movement of the lever 28 forces the collar 41 inwardly on the shaft 7, raises the locking member 36 into the slots 35, and locks the shaft 7 and units and tens disks 8 and 9 to rotate in unison (Fig. 8). The multiplier button z representing 8 is now operated and the lever 71 is pulled forwardly, which first operates the mechanism to advance the carriage one step to the right, to position the gears of the indicating wheels 75 in mesh with the gears 145 associated with the units disks Fig. 13. Simultaneously with the above movements, the finger 72 in its travel over the rack 75 is released from the pin 73 and permits the spring 69 to rotate the shaft 7 with the controlling disks keyed thereto until the arm 67 associated therewith contacts with the depressed multiplier key z (Figs. 7 and 8), at approximately this same time the arm 186 has been forced to a position in front of the spring pressed pawl 187, and the pin 133 on the shaft 70 has completed its movement through the slot or cut out 132 in the arm 131, and is forcing the arm forwardly, which operates the plunger 90 frame 138 to permit the springs 146 to rotate the gears 143 to force the plungers 142' into the stepped recesses of the controlling disks positioned at the end of the same, and in this movement the units and tens plungers 95 associated with the respective operated multiplicand keys will rest in the respective steps B and C of the sectors A* of the units and tens disks of the first two pairs of disks to the right. It will be observed by reference to Fig. 15 that the first step movement of the carriage has intermeshed the indicator wheels with the gears associated with the units plungers and that the movement of the units plungers into their respective 100 seats in their respective controlling disks will rotate the indicator wheels to such position as to present the figures 2—2 thereon upwardly in line with the sight openings 4. During this previously mentioned operation, 105 the plungers associated with the tens controlling disks in their movement to their seats have rotated the gears 145 associated therewith, but said gears not being in mesh with the indicator wheels do not rotate the 110 same. As the plunger controlling frame is being moved forwardly, the shaft 137 is also being operated, which draws the trip arm 160 forwardly, which through its respective connections forces the plate 157 rearwardly, 115 which permits the springs 154 to draw the pawls 150 and 150' inwardly as in Fig. 14, which prevents the springs 149' on the rearward movement of the plunger controlling slide 138 from forcing the racks 142' rearwardly into one of the steps 151, until such time as it is necessary to carry a tens numeral from one indicator wheel to another at the left thereof.

The units of the answer having been 120

transmitted to the indicator wheels, the lever 71 is moved rearwardly and in its movement the carriage advancing mechanism is first operated and the carriage is advanced another step to the right, which disconnects the indicator wheels from the gears associated with the units plungers and intermeshes the same with the gears associated with the tens plungers, but the indicator 10 wheel to the right having been intermeshed with the first units disk during the previous movements will be disengaged therefrom and permitted to remain idle, as the units of the result 2 has been recorded thereon and 15 is displayed beneath one of the openings 4. Further movement of the lever 71 rearwardly forces the slide 138 rearwardly which removes the plungers from their seats, and forces the racks associated with the operated multiplicand buttons rearwardly. The indicator wheels now being in gear with the gears associated with the tens plungers will be rotated on the return movement thereof a distance equal to the seven 20 steps in the tens controlling disks, and will thus display through the openings 4 the respective numerals 9 tens and 7 hundreds, as the tens wheel had recorded thereon two steps from its previous engagement with the 25 gear associated with the second units disk, and the hundreds wheel had previously been in engagement with a gear associated with a plunger which had rested on the segment A° of the third units disk, thus the resultant 30 sum of 99 multiplied by 8 which equals 792 is displayed through the openings 4. In the operation of the machine the disks associated with the non-operated multiplicand keys will present to the plungers on the 35 actuation of the multiplier lever their segments A°, which will prevent the plungers from moving any steps in either direction. While the rotation of the indicator wheels is taking place the flexible end of the trip bar 40 160 is passing over its associated crank arm 164 without operating the same. Simultaneously with the previously mentioned operation, the arm 186 in its return movement actuates the trip 187, which, through its 45 connections operates the restoring plate 21 causing the beveled lugs 23 to contact with the shoulders and restore the depressed multiplicand and multiplier buttons to their normal position. The restoring of the multiplicand buttons will not in any way effect 50 the position of the arms 16 as the disks are now held in locked position on the shaft 7, and will remain in such position until the lever 28 is thrown to its normal inoperative 55 position. As the lever 71 has about completed its return movement, the arm 72 strikes the pin 78 and forces the arm 65 rearwardly, which, through suitable connections causes the arm 67 to assume the dotted line 60 position—Fig. 7. The lever 28 is now

moved rearwardly which unlocks the disks 8 and 9 from the shaft 7, and operates the bar 34 to move the segments 11 against the action of the springs 14 and cause the same to assume their full line position, as in Fig. 4.

To prove the answer and clear the indicator wheels, the carriage reversing mechanism (Figs. 17 and 19) is thrown into operation, which changes the movement of the carriage from left to right to right to left on the movement of the lever 71, and one complete operation of this lever will rotate the indicator wheels in a reverse movement to that which was employed when the answer was being obtained.

In Figs. 20, 21 and 22 there is disclosed the diagrammatic multiplication of a difficult problem, the forward movement of the carriage and the numbers displayed by the indicator wheels during each forward and backward movement of the multiplier lever in obtaining the answer, and the rearward movement of the carriage and the numbers displayed by the indicator wheels during each forward and rearward movement of the multiplier lever in proving the answer. By reference to these figures, it will be apparent that each button of the multiplier set representing the respective multiplier numerals is depressed in a direction from right to left, one at a time, and after each one is depressed, the multiplier lever is moved forwardly which rotates the indicator wheels to have recorded thereon the units of the result, then the lever is moved rearwardly which movement adds to the units already recorded on the wheels the multiplication of the tens; viz—in the result of 69389 multiplied by 9, the units numerals of the result 4—1—7—2—1 are first recorded on the wheels on the forward movement of the lever, and to this sum is added the result of the multiplication of the tens, totaling 6—2—4—5—0—1. To the sum already recorded on the indicator wheels is added, on each depression of a multiplier button and the movement of the multiplier lever in both directions, the sum of the multiplication, and this takes place until the final result has been obtained.

In proving a multiplied sum, the same operations are performed as when obtaining the answer, but the multiplier buttons are operated in their inverse order.

It will be apparent that I have constructed a machine that is adapted for the multiplying of any given numbers and one which successively discloses each multiplied sum of the multiplicand by the depressed multiplier button, together with the result previously recorded on the indicator wheels; one by which the answer of the multiplied sum is capable of being proved, and one which is simple in construction, may be constructed.

at little cost and is well adapted for the purposes described.

Having thus described my invention what I claim as new and desire to protect by Letters Patent is:—

1. A calculating machine comprising multiplicand and multiplier keys, controlling means, means for simultaneously setting the controlling means in accordance with the operated multiplicand keys, means for operating the set controlling means in accordance with the operated multiplier key, and means for displaying the resultant sum represented by the depressed keys.
2. A calculating machine comprising multiplicand and multiplier keys, controlling means, means for simultaneously setting the controlling means in accordance with the operated multiplicand keys, means for operating the set controlling means in accordance with the operated multiplier key, and means controlled by the controlling means for displaying the resultant sum represented by the depressed keys.
3. A calculating machine comprising multiplicand and multiplier keys, controlling means, means for simultaneously setting the controlling means in accordance with the operated multiplicand keys and for locking the said set controlling means to be operated in unison, means for operating the set and locked controlling means in accordance with the operated multiplier keys, and means for displaying the resultant sum represented by the depressed keys.
4. A calculating machine comprising multiplicand and multiplier keys, controlling means, means for simultaneously setting the controlling means in accordance with the operated multiplicand keys, means for operating the set controlling means in accordance with the operated multiplier key, a movable carriage, indicating mechanism carried thereby, and means associated with said indicating mechanism and said controlling means for operating said indicating mechanism to display the resultant sum represented by the depressed keys.
5. A calculating machine comprising multiplicand and multiplier keys, controlling means, means for simultaneously setting the controlling means in accordance with the operated multiplicand keys, means for operating the set controlling means in accordance with the operated multiplier key, a movable carriage, indicating mechanism carried thereby, means operated on each operation of said set controlling means for moving the carriage by a step motion in one direction, means associated with said indicating mechanism and co-operating with said controlling means for operating said indicating mechanism to display the resultant sum represented by the depressed keys, means for reversing the direction of move-

ment of the carriage, and means operated on each operation of said set controlling means for moving the carriage by a step motion in a reverse direction to clear said indicating mechanism.

6. In a calculating machine comprising multiplicand and multiplier keys, controlling means comprising a plurality of recess disks arranged in duplicate pairs, means for simultaneously rotating the controlling means to set the same in accordance with the operated multiplicand keys and for locking said set controlling means to be operated in unison, means for operating the locked controlling means in accordance with the operated multiplier keys, and means co-operating with the controlling means for indicating the sum represented by the operated keys.

7. A calculating machine comprising controlling means, a plurality of sets of operating keys, means for simultaneously setting the controlling means in accordance with the operated keys of one set, means for operating the set controlling means in accordance with the operated keys of another set, and means co-operating with said controlling means for indicating the sum represented by the operated keys.

8. A calculating machine comprising a plurality of sets of numeral keys, controlling means provided with stepped seats, means for simultaneously setting the controlling means in accordance with the operated keys of one set and for locking the said set controlling means to be operated in unison, means for operating the set controlling means in accordance with the operated key of another set, indicating mechanism, and means associated with said indicating mechanism and for receiving in the stepped seats of said controlling means to operating said indicating mechanism to display the resultant sum represented by the operated keys.

9. A calculating machine comprising a plurality of sets of numeral keys, rotatably mounted controlling disks arranged in duplicate pairs and provided with stepped seats, means for simultaneously rotating said controlling disks in accordance with the operated keys of one set and for locking the same to be operated in unison by another set, means for rotating said locked disks in accordance with the operated key of another set, a carriage carrying a plurality of indicator wheels, a plunger associated with each of said controlling disks and adapted to co-operate with the stepped seats therein, a gear associated with each plunger, means for moving said plungers into and out of said stepped seats, and means for intermittently moving said carriage to position certain of said indicator wheels in co-operative relation with certain of said gears on the movement of said plungers into said

seats, and to position certain of said indicator wheels in coöperative relation with certain other of said gears on the movement of said plungers out of said seats.

- 5 10. A calculating machine comprising a plurality of sets of numeral keys, rotatably mounted controlling disks arranged in duplicate pairs and provided with stepped seats, means for simultaneously rotating 70
10 said controlling disks in accordance with the operated keys of one set and for locking the same to be rotated in accordance with the operated keys of another set, means for rotating said locked disks in accordance with 75
15 the operated key of another set, a carriage carrying a plurality of indicator wheels, a plunger associated with each of said controlling disks and adapted to coöperate with the stepped seats therein, a gear associated with 80
20 each plunger and rotated by the movement thereof, means for moving said plungers into and out of said stepped seats, means for intermittently moving said carriage in one direction to position certain of said indicator 85
25 wheels in coöperative relation with certain of said gears on the movement of said plungers into said seats and to position certain of said indicator wheels in coöperative relation with certain other of said gears
30 on the movement of said plungers out of said seats, and means for reversing the direction of movement of said carriage.

11. A calculating machine comprising a plurality of sets of keys, controlling means, 35 means for simultaneously setting the controlling means in accordance with the operated keys of one set and for locking the same to be operated in unison by the keys of another set, means for operating the set 40 controlling means in accordance with the operated key of another set, and means co-operating with said controlling means for indicating the sum represented by the operated keys.

- 45 12. A calculating machine comprising a plurality of sets of numeral indicating keys, controlling means, means for setting the controlling means in accordance with the operated keys of one set and for locking the 50 same to be operated in unison by the keys of another set, means for operating the set controlling means in accordance with the operated key of another set, indicating means, and means associated with the controlling means and co-operating with said indicating means for indicating the sum represented by the operated keys.

- 55 13. A calculating machine comprising a plurality of sets of numeral indicating keys, 60 means for retaining the keys in their operated position, controlling means, means for setting the controlling means in accordance with the operated keys of one set and for locking the same to be operated in unison 65 by the keys of another set, a movable car-

riage, indicator wheels carried thereby, plungers associated with said indicator wheels and coöperating with the controlling means, means operated in one direction for advancing the carriage, for operating the 70 set controlling means to present the same to the plungers in accordance with the operated key of another set and for permitting the plungers to coöperate with said controlling means and operated in the opposite direction to restore the plungers to normal position and permit the set controlling means to be restored to set position, means for restoring said controlling means to set position, and devices for restoring the operated keys to their normal position on the restoring of the plungers to their normal position.

14. A calculating machine comprising a plurality of sets of numeral indicating keys, 85 controlling disks arranged in pairs and each pair rotatably mounted, said disks provided on their peripheral edges with sets of stepped seats of different depths, means for rotating said pairs of disks and locking the same in 90 accordance with the operated keys of one set, means for rotating said locked disks in accordance with the operated key of another set, indicator wheels provided with numerals, and means associated therewith for 95 seating in the stepped seats presented thereto for operating said indicator wheels to display the numerals thereon in accordance with the depth of said seats.

15. A calculating machine comprising a 100 plurality of sets of numeral indicating keys, controlling means provided with recesses of various depths, means for independently operating said controlling means and locking the same in accordance with the operated 105 keys of one set, means for operating said locked disks in accordance with the operated key of another set, a carriage carrying a plurality of indicator wheels, plunger mechanism associated with each of said controlling disks and for coöperating with the stepped seats therein, means for moving said plunger mechanism into and out of said stepped seats, means for intermittently moving said carriage to position said indicator wheels in 110 coöperative relation with certain of said plunger mechanisms on the movement of said mechanisms toward said seats and to position said indicator wheels in coöperative relation with certain other of said plunger mechanisms on the movement of said mechanisms from said seats, and means operated 115 by the complete rotation of one of said indicator wheels for permitting the plunger mechanism to rotate the wheel adjacent said mentioned wheel a distance equal to one step more than the depth of the recess into which said plunger mechanism has been seated.

16. In a calculating machine, the controlling device consisting of a plurality of ro- 120

- tatably mounted means arranged in duplicate pairs and provided with sets of recesses of different depths, means for operating said controlling means, indicating mechanism provided with numerals, and means associated therewith for seating in the recesses presented thereto for operating said indicating mechanism to display the numerals thereon in accordance with the depth of said recesses.
17. In a calculating machine, the means for transmitting to the indicating mechanism the initial operation of a plurality of rotatably mounted suitable keys, consisting of means arranged in duplicate pairs and each provided with sets of recesses of different depths, and means associated with the indicating mechanism, for displaying the numerals thereon in accordance with the depth of said recesses.
18. In a calculating machine, the means for transmitting to the indicating mechanism the initial operation of suitable keys, consisting of disks arranged in duplicate pairs and each pair rotatably mounted, said disks provided on their peripheral edges with sets of stepped seats indicating mechanism provided with numerals, and means associated therewith for seating in said stepped seats presented thereto for operating said indicating mechanism to display the numerals thereon in accordance with the depth of said seats.
19. In a calculating machine comprising operating keys, controlling means provided with recesses of different depths, a carriage carrying indicating mechanism, plungers associated with said controlling means and adapted to coöperate with the recesses thereof, a gear mechanism associated with each plunger and operated by the movement thereof, means for moving said plungers in and out of said recesses, means for moving said carriage to position certain of said indicating mechanisms, in coöoperative relation with certain of said gear mechanisms on the movement of said plungers into said recesses, and to position certain of said indicating mechanism in coöoperative relation with certain other of said gear mechanisms on the movement of said plungers out of said recesses, and means operated by the complete operation of one of said indicating mechanisms for permitting the plunger to operate the mechanism adjacent to said mentioned mechanism a distance equal to one step more than the depth of the recess into which said plunger mechanism has been seated.
20. A calculating machine comprising a plurality of sets of numeral indicating keys, controlling disks arranged in duplicate pairs and each pair rotatably mounted, means for simultaneously rotating said pairs of disks in accordance with the operated keys of one set and for locking the same to be rotated in unison in accordance with the operated keys of another set, means for rotating said locked disks in accordance with the operating keys of another set, and means for displaying the resultant sum represented by the depressed keys.

In testimony whereof I have signed my name to this specification in the presence of two subscribing witnesses.

HARRY WALTER JONES.

Witnesses:

HARRY A. TOTTEN,
D. B. RICHARDS.

Copies of this patent may be obtained for five cents each, by addressing the "Commissioner of Patents, Washington, D. C."

It is hereby certified that in Letters Patent No. 1,140,684, granted May 25, 1915, upon the application of Harry Walter Jones, of San Francisco, California, for an improvement in "Computing-Machines," errors appear in the printed specification requiring correction as follows: Page 10, lines 13 and 14, strike out the words "a plurality of rotatably mounted"; same page, line 15, after the word "of" insert the words *a plurality of rotatably mounted*; and that the said Letters Patent should be read with these corrections therein that the same may conform to the record of the case in the Patent Office.

Signed and sealed this 22nd day of June, A. D., 1915.

[SEAL.]

J. T. NEWTON,

Acting Commissioner of Patents.
